United States Patent Office.

JAMES H. PRESTON, OF JEFFERSON CITY, MISSOURI.

Letters Patent No. 97,961, dated December 14, 1869.

IMPROVED SIDE-SADDLE TREE.

The Schedule referred to in these Letters Patent and making part of the same.

To all whom it may concern:

Be it known that I, JAMES H. PRESTON, of Jefferson City, in the county of Cole, and State of Missouri, have made certain new and useful Improvements in Side-Saddle Trees; and I do hereby declare the following to be a full and true description thereof, reference being had to the accompanying drawings, and to the letters of reference marked thereon.

This improvement relates more especially to the manner of arranging a removable and adjustable leg-rest to the ordinary side-saddle-tree body, and to the manner of arranging the stirrup-straps, in accordance with the adjustment of the leg-rest, as aforesaid.

To enable those herein skilled to make and use my said improvement, I will now more fully describe, in its more usual form and application, referring herein to the accompanying

Figure 1 as a side view; to

Figure 2 as a front view of the side-saddle tree, fitted in proper form for covering and use; and to

Figure 3 as bottom plan of the leg-rest removed, to show the adjustable tablet and its connections, as hereafter more fully explained.

I form the tree-body A of the usual material, braced and joined in the usual form and manner.

The front A' of said body is, however, made so as to be disconnected from the leg-rest or horns B.

The leg-rest is shaped as ordinarily, but in order to prevent loss or damage of the tree, by breakage of the leg-rest, and especially in order that the leg-rest may be turned so as to enable the rider to sit "right" or "left" upon the saddle, and thus avoid inconvenience, cramping, or soreness by a continuous posture in either of said positions, I have arranged the leg-rest B to be readily turned about in a half circle, and secured in the manner following:

To the under side b of said rest is secured, by suitable screws or otherwise, a metallic plate, C, under which is the tablet D, pivoted, by the screw d, upon said plate C.

In order to prevent the plate C from turning a greater arc than (about) one hundred and eighty degrees, a pin, d', of the tablet D, is guided in the semi-circular slot c of the plate C.

At each end of its circular stroke, the plate C is held by the notches d' of the tablet D, engaging upon a spring-latch, E, which is suitably secured in the rest B, and which may be depressed into a suitable groove to release the tablet D when it is desired to turn the leg-rest.

The tablet D is secured, by screws or other means, firmly to the top of the front A' of the tree-body, so that when the latch-spring E is in engagement on the tablet-notches, the leg-rest is fixed in its position relative to the tree-body; but when the spring E releases the notches d', the leg-rest may be turned in a half-circular arc, so as to enable the rider to rest the leg, which before was in the stirrup-rest, on the leg-rest.

In order that the stirrup may be adjusted in accordance with the movement of the leg-rest, I have attached the stirrup-strap F, by a hasp, f, to the front A' of the tree-body about centrally. Said strap may then pass down either side, to engage about a button or screw, g, and thus be on the right or left side of the tree-body, as may be required.

It will be seen that my said adjustable leg-rest not only enables the user to occupy the seat, to avoid great discomfort from long continuance in one position, but in case of breakage of a leg-rest, a new one may readily replace the one thus made useless, without disuse of the whole tree-body; and, lastly, the joint of the tablet D, upon the top of the body-front A', may be used to secure the tree-covering or padding, without the employment of screws or nails in such place as to render the same inconvenient in sitting upon the saddle, or difficult of attachment.

The advantage arising from the change of position here made practicable for the rider, is also greatly beneficial to the horse or other animal, in a manner readily perceivable.

Lastly, if it be desirable, the usual stirrup-bar may be used on both sides of the tree for the stirrup-attachment.

Having thus fully described my invention,

What I claim, is—

1. The adjustable leg-rest B, when combined with a tree-body, A A', substantially as set forth.

2. The leg-rest B, the plate C, tablet D, pin d, and slot c, when arranged and combined with the tree-body, substantially as set forth.

3. The adjustable stirrup-strap F, arranged with an adjustable leg-rest, B, and tree-body C, all as and for the purpose set forth.

In testimony of said invention, I hereunto set my hand, in the presence of—

J. H. PRESTON.
